UNITED STATES PATENT OFFICE.

THOMAS D. FINIZIO, OF KITCHAWAN, NEW YORK.

ATTACHING-PLUG.

1,231,634.

Specification of Letters Patent. Patented Feb. 24, 1920.

Application filed March 3, 1916, Serial No. 31,831. Renewed July 14, 1919. Serial No. 310,376.

To all whom it may concern:

Be it known that I, THOMAS D. FINIZIO, a citizen of the United States, residing at Kitchawan, Westchester county, in the State of New York, have invented certain new and useful Improvements in Attaching-Plugs, of which the following is a full, clear, and exact specification.

This invention relates to an improvement in attachment plugs and has for its object to provide a plug which may be secured to or removed from a socket without twisting the conductors which connect the plug to the electrically operated device.

15 A further object is to provide a plug which will permit of the electrically operated device being moved freely during use without twisting the connecting conductors.

20 A further object is to provide a plug having a set of contacts adapted to engage the contacts of a socket, and a second set of contacts engaging the contacts of the first-named set and being rotatable with respect thereto.

25 A further object is to provide a plug comprising a casing having a set of contacts, and a member rotatable within said casing and carrying a set of contacts engaging the contacts of the first-named set.

30 A further object is to provide a plug which is of simple construction and to which the connecting conductors may be easily and quickly attached.

Other objects will in part be obvious and in part be pointed out hereinafter.

To the attainment of the aforesaid objects and ends, my invention consists in the novel details of construction, and in the combination, connection and arrangement of parts hereinafter more fully described and then pointed out in the claims.

35 In the accompanying drawings showing an illustrative embodiment of the invention—

40 Figure 1 is a view in side elevation of the attachment plug;

Fig. 2 is a sectional view of the socket engaging portion of the plug;

Fig. 3 is a similar view of the body portion of the plug removed from the socket engaging portion thereof;

Fig. 4 is a plan view of the plug, and

Fig. 5 is a perspective view of the rotatable member and the contacts carried thereby.

Referring to the drawings the attachment

plug comprises a casing consisting of a socket-engaging portion 10 and a body portion 11 detachably secured to the socket-engaging portion and normally locked against movement with respect thereto whereby the attachment plug may readily be inserted in or withdrawn from an electric socket.

The socket-engaging portion 10 comprises a metallic shell having a threaded annular wall 12 provided at one of its ends with an inwardly extending flange 13 to which is secured a base consisting of two spaced metallic plates 14, 15 engaging the outer and inner surfaces of the flange 13 and spaced from one another by insulating material 16. The plates 14 and 15 are provided with centrally positioned apertures to receive a metallic member 17 which extends through the apertures and is insulated from the plates by the insulating material 16. As shown the metallic member 17 is in the form of a pin having headed ends 18, 18 engaging the insulating material 16. When the attachment plug is positioned within a socket the metallic shell will engage one of the socket terminals and the metallic member will engage the other thereof.

The body portion 11 of the attachment plug is preferably formed of insulating material and comprises a head portion 19 and an annular flange 20 adapted to extend within the shell of the socket-engaging portion 10 and being of substantially the same height as the wall 12 thereof. The flange 20 is provided in its outer surface with a thread 21 adapted to engage the thread of the wall 12 of the shell whereby the parts may be detachably secured to one another.

In order to hold the parts against relative movement to enable the attachment plug to be screwed into and unscrewed from the socket, the body portion 11 is provided with a spring 22 having a projection 23 adapted to project through an aperture 24 formed in the wall 12 of the shell when the parts are properly assembled. When it is desired to separate the parts it is merely necessary to press upon the projection 23 and force it inwardly until it is out of engagement with the opening 24 whereupon the body portion 11 may be unscrewed and detached from the socket-engaging portion 10.

The head 19 of the body portion has an opening 25 therethrough to receive a cable 26 or the like and is further provided with a recess 27 surrounded by a seat 28 and com-

municating with the aperture 25 and the chamber 29 formed by the annular flange 20.

Positioned within the chamber 29 and free to rotate therein is a block 30, preferably formed of insulating material, which rests upon the seat 28 and has a reduced portion 31 extending within the recess 27. The block 30 is provided with an aperture registering with the aperture 25 in the head 10 19 to receive the cable 26.

Mounted upon the block are a pair of resilient contacts 32 and 33 having oppositely extending free ends 34 and 35 respectively arranged in superimposed relation to one another. When the parts of the attachment plug are assembled the free end 34 of the contact 32 engages the inner end of the metallic member 17, and the free end 35 of the contact 33, which is preferably forked, as shown in Fig. 5, engages the inner surface of the plate 15 of the base of the metallic shell. The contacts 32 and 33 are so proportioned that, when the parts of the plug are assembled, their free ends 34 and 35 will be depressed slightly whereby, owing to the resiliency of the contacts, said ends will be pressed against the metallic member 17 and the plate 15 thus insuring good electrical connections therewith.

The conductors 36 and 37 of the cable 26 are secured to the contacts 32 and 33 in any suitable manner.

In operation the cable 26 is passed 35 through the aperture 25 in the head 19 of the body portion 11 and through the aperture in the block 30 whereupon the ends of the conductors 36 and 37 are connected to the contacts 32 and 33. The block 30 is then 40 positioned within the chamber 29 in engagement with the seat 28 after which the body portion 11 is secured to the socket-engaging portion 10 as above set forth, the portions being automatically locked together 45 by the engagement of the projection 23 on the spring 22 with the aperture 24 in the wall 12 of the metallic shell.

The attachment plug may then be screwed 50 within an electric socket by a rotary movement of the casing, the thread of the wall 12 of the metallic shell engaging the threaded sleeve forming a part of the sockets of the usual and well known construction. As the casing of the plug and the block 30 55 are free to rotate relatively to one another the rotary movement of the casing necessary to secure the plug within the socket will not cause a twisting of the cable. Furthermore, when the plug is positioned within the 60 casing the electrically operated device which is connected to the other end of the cable 26 may be freely moved in any direction without twisting the cable as any movement of such device which would tend to twist the 65 cable will merely cause the cable and the

block 30 secured thereto to rotate relatively to the casing of the plug. As the free ends 34 and 35 of the contacts 32 and 33 are maintained in pressing engagement with the contacts of the socket-engaging member 10, the 70 electrical connections will not be disturbed by the rotation of the block 30 within the casing of the plug.

Having thus described my said invention, what I claim and desire to secure by Letters 75 Patent is:—

1. An attachment plug comprising a casing having contacts adapted to engage the contacts of a socket, a member rotatably positioned within said casing, and contacts 80 carried by said member and engaging said first mentioned contacts, said casing being provided with an opening in one of its walls to receive conductors adapted for connection to the contacts on said rotatable member, 85 substantially as specified.

2. An attachment plug comprising a casing having contacts adapted to engage the contacts of a socket, said casing having a base and a head, a member rotatably positioned within said casing, and contacts carried by said member and engaging said first mentioned contacts, said head being provided with an opening to receive conductors adapted for connection to the contacts on said rotatable member, substantially as specified. 95

3. An attachment plug comprising a casing consisting of a plurality of detachably connected parts and having a set of contacts, a member positioned wholly within said casing and rotatable with respect thereto, and contacts mounted upon said member and engaging the contacts of said set, one of said parts being provided with an opening to receive conductors adapted to be connected to the contacts on said member, substantially as specified. 100

4. An attachment plug comprising a casing consisting of a socket-engaging portion 110 and a body portion detachably secured thereto, said socket-engaging portion having a set of contacts, a member contained within said casing and rotatable with respect thereto, and contacts mounted upon said member and engaging the contacts of said set, substantially as specified. 115

5. An attachment plug comprising a casing consisting of a hollow socket-engaging portion and a hollow body portion detachably secured thereto and extending therein, said socket-engaging portion having a set of contacts, a rotatable member positioned within said hollow body portion, and contacts mounted upon said rotatable member and engaging the contacts of said set, substantially as specified. 120

6. An attachment plug comprising a casing consisting of a socket-engaging portion and a body portion detachably secured 125

3

thereto, said portions being provided with co-acting locking means to hold them in their assembled position, said socket-engaging portion having a set of contacts, a member contained within said casing and rotatable with respect thereto, and contacts mounted upon said member and engaging the contacts of said set, substantially as specified.

7. An attachment plug comprising a casing having a set of contacts, said casing being provided with a seat, a member positioned wholly within said casing and resting upon said seat, said member being rotatable with respect to said seat, and contacts mounted upon said rotatable member and engaging the contacts of said set, substantially as specified.

8. An attachment plug comprising a casing having a set of contacts, said casing being provided with a seat, a member positioned wholly within said casing and resting upon said seat, said member being rotatable with respect to said seat, and resilient contacts mounted upon said rotatable member and engaging the contacts of said set, substantially as specified.

9. An attachment plug comprising a socket-engaging portion consisting of a metallic shell having a base and a metallic member carried by said base and insulated therefrom, a body portion detachably secured to said socket-engaging portion and forming a casing therewith, a member positioned within said casing and free to rotate with respect thereto when said portions are assembled, and a pair of contacts mounted upon said member and engaging said base and said metallic member respectively, substantially as specified.

10. An attachment plug comprising a socket-engaging portion consisting of a metallic shell having a base and a metallic member carried by said base and insulated therefrom, a body portion of insulating material detachably secured to said socket-engaging portion and forming a casing therewith, a member positioned within said casing and free to rotate with respect thereto when said portions are assembled, and a pair of contacts mounted upon said member and engaging said base and said metallic member respectively, substantially as specified.

11. An attachment plug comprising a socket-engaging portion consisting of a metallic shell having a base and a metallic member carried by said base and insulated therefrom, said metallic member extending inwardly of said shell, a body portion detachably secured to said socket-engaging portion and forming a casing therewith, a member positioned within said casing and free to rotate with respect thereto when said portions are assembled, and a pair of contacts mounted upon said member and engaging said base and said metallic member respectively, substantially as specified.

12. An attachment plug comprising a socket-engaging portion consisting of a metallic shell having a base and a metallic member carried by said base and insulated therefrom, said metallic member extending inwardly of said shell, a body portion detachably secured to said socket-engaging portion and forming a casing therewith, a member positioned within said casing, and a pair of contacts mounted upon said member and having superimposed free ends engaging said base and said metallic member respectively, substantially as specified.

13. An attachment plug comprising a metallic shell having an annular wall and a base, a metallic member carried by said base and insulated therefrom, a body portion detachably secured to said shell, said body portion having a head and an annular flange extending within said shell and engaging the annular wall thereof, a member engaging said head and positioned within said annular flange, and a pair of contacts mounted upon said member and engaging the base of said shell and said metallic member respectively, substantially as specified.

14. An attachment plug comprising a metallic shell having an annular wall and a base, a metallic member carried by said base and insulated therefrom, a body portion detachably secured to said shell, said body portion having a head and an annular flange extending within said shell and engaging the annular wall thereof, said head having a recess formed therein and having a seat surrounding said recess, a member engaging said seat and having a reduced portion extending within said recess, and a pair of contacts mounted upon said member and engaging the base of said shell and said metallic member respectively, substantially as specified.

Signed at the city of New York, in the 11th county and State of New York, this 11th day of February, one thousand nine hundred and sixteen.
